UNITED STATES PATENT OFFICE.

JOHN C. RINGE, OF BRIDGEPORT, CONNECTICUT, ASSIGNOR TO THE SINGER MANUFACTURING COMPANY, A CORPORATION OF NEW JERSEY.

ROTARY-HOOK SEWING-MACHINE.

1,292,063.

Specification of Letters Patent. Patented Jan. 21, 1919.

Application filed February 9, 1916. Serial No. 77,123.

To all whom it may concern:

Be it known that I, JOHN C. RINGE, a citizen of the United States, residing at Bridgeport, in the county of Fairfield and State of Connecticut, have invented certain new and useful Improvements in Rotary-Hook Sewing-Machines, of which the following is a specification, reference being had therein to the accompanying drawings.

10 This invention relates to an improvement in sewing machines adapted for operation at high speed and employing loop-takers, more particularly of that class comprising a rotary loop-seizing member formed with 15 an axial thread-cavity in which is journaled a thread-case restrained against rotation with said member; and it has for its primary object the provision of means, for handling the needle-thread in the casting of 20 loops thereof around the mass of lower thread, of such character as to accommodate a lower thread capacity of the loop-taker greatly exceeding that which has been practicable heretofore in this type of machine.

25 In the development of high-speed sewing machines, or those producing 3500 to 5000 stitches per minute, it is of the utmost importance that all harsh motions of operative parts be avoided, that the friction of the 30 moving parts be maintained at a minimum to prevent overheating and other difficulties, and that the action of the thread-engaging elements upon the needle-thread may be gradual rather than abrupt so as to avoid 35 injury or kinking of the thread resulting in its breakage or formation of knots in the completed stitches. In recognition of these requirements, it has become the established practice in the production of high-speed 40 lock-stitch machines for use in the manufacture of clothing to employ a comparatively small mass of lower thread in order that the loop-taker may be of correspondingly small size so as to permit of the utilization 45 of a comparatively short length of needle-thread to be manipulated in the casting of loops of the same about the mass of lower thread.

The present invention constitutes a radical departure from the existing practice above described, in that it involves, in its preferred embodiment, the employment of a thread-case of greatly enlarged capacity in

a form of loop-taker which is commercially established in practical and successful operation at high speed, in combination with a rotary take-up having a thread-engaging element whose action upon the thread throughout its operative period in each stitch-forming cycle is positive during which period it 55 performs an accelerated movement within a single rotation traversed while the loop-taker is performing two rotations.

While a vibratory take-up element may be employed in high-speed machines wherein 60 a normal amount of needle-thread is to be handled, such form of take-up becomes noisy and insufficiently controls the thread when its scope is enlarged to accommodate an abnormally long length of thread; for which 65 reason the adoption of the rotary form of take-up is imperative. The employment of an abnormally large thread-case in the rotary hook type of loop-taker involves a correspondingly large bearing surface between 70 the same and the loop-taking member which precludes the turning of the latter at a speed of more than two rotations for each reciprocation of the needle and each rotation of the 75 take-up, by reason of the excessive friction 80 and consequent overheating which would be produced by a more rapid movement of the loop-taking member relatively to the needle-bar reciprocations.

The proper manipulation of the needle-thread above the work requires that the thread-drawing action be started promptly as the thread-loop arrives at cast-off position in the loop-casting operation, and shall be completed in the setting of the stitch while 85 the needle remains above the work, and that the thread shall be thereafter slackened preparatory to the descent of the needle-eye through the work. The relative speed of rotation between the loop-taking member 90 and the needle-actuating shaft, and hence of the take-up, being fixed as before described, as well as the timing of the requisite take-up action, the movement of the thread-engaging take-up element at the same rate 95 of speed as the needle-actuating shaft is not sufficiently rapid, and hence means are provided, according to the present invention, for imparting to it an accelerated movement 100 during its loop-drawing and stitch-setting 105 action.

In the preferred embodiment of the present invention, I employ the form of loop-taker represented in the United States patent to P. Diehl and M. Hemleb, No. 5 1,149,504, of August 10, 1915, but with certain added features to facilitate the casting of the needle-thread loops about the mass of lower thread and to insure ample lubrication of the bearing between the annular 10 raceway upon the inner wall of the loop-taking member and the bearing rib upon the thread-case within the same. As preferably constructed, the thread-case has upon the inner end of its cast-off side a peripheral 15 segmental guard-rib adapted to shield the needle-thread loops from injurious contact with the peripheral bearing rib as they are drawn off the loop-taker beak, while contributing to the control of the thread-loops 20 under the action of the take-up.

One of the arms by which the loop-taker body is secured to the axial hub is formed with a radial lubricant duct communicating at its outer end with the raceway for the 25 bobbin-case bearing rib, and communicating at its opposite end with a lateral branch of an axial lubricant passage in the loop-taker shaft which is formed with a second branch communicating with a lubricant passage in 30 the bearing in which said shaft is journaled; whereby the loop-taker raceway may be supplied with lubricant from the upper side of the machine bed-plate without turning over the machine and without liability of soiling 35 the mass of lower thread. The radial lubricant duct of the loop-taker is preferably formed with an enlargement affording a lubricant cavity packed with wicking or other absorbent material and open adjacent 40 the hub for the reception of lubricant, when its introduction at this point is desired.

The outer face of the thread-case has upon the cast-off side a forwardly projecting loop-absorbing flange at the extremity of which it is formed with a notch entered by and 45 loosely embracing the rearwardly projecting finger of a stationary holding member, between the extremity of which finger and the bottom of said notch the lower thread is 50 confined in a substantially straight passage from the delivery side of the thread-case to the work. The thread-case has nearly diametrically opposite said notch a shoulder 55 engaged periodically by a laterally extending vibratory finger of a rock-shaft operatively connected with the feed-lift rock-shaft, whereby the thread-case is slightly turned once only in each stitch-forming cycle 60 to open a loop-releasing passage between the stationary holding finger and the side of the embracing notch of the thread-case.

The invention will be understood by reference to the accompanying drawings, in

which Figure 1 is a side elevation, with the frame partly in section, of a sewing machine embodying the present improvements, and Fig. 2 is a view of the under side of the same. Fig. 3 is an end elevation of the machine with the bed-plate in section. Fig. 4 65 is an enlarged sectional elevation of the forward end of the loop-taker shaft with its bearing and the loop-taker mounted thereon. Figs. 5 and 6 are perspective views representing the loop-taker in different operative 70 positions and Fig. 7 a perspective view representing the loop-seizing member and the thread-case carrier section detached, with the thread-case opening mechanism. Fig. 8 is a perspective view of the thread-case and 75 its stationary holder, viewed from the front side. Fig. 9 is a perspective view representing the loop-taker from the front end with the loop-seizing member in a different position from those represented in Figs. 5 and 80 6. Figs. 10, 11 and 12 are views representing diagrammatically the relation of the loop-taker and the take-up in different 85 stages of a stitch-forming cycle, and Fig. 13 is a sectional plan view through the head of 90 the bracket-arm to show the construction of the take-up and its relation to the needle-actuating shaft.

The frame of the machine is constructed with the usual bed-plate 1 from which rises 95 the bracket-arm comprising the hollow standard 2 and tubular overhanging arm 3 terminating in the head 4 in which is journaled the reciprocating needle-bar 5 carrying the eye-pointed needle 6. The needle-bar is connected by means of the usual pitman connection 7 with the actuating crank-pin 8' carried by the crank-plate 8 fixed upon the main or needle-actuating shaft 9 which is provided with the usual balance-wheel 10. The main-shaft 9 has fixed thereon the bevel gear 11 meshing with the bevel pinion 12 upon the upper end of the upright shaft 13 suitably journaled in bearings of the standard 2 and having fixed upon its 110 lower end the bevel pinion 14 which meshes in turn with the bevel pinion 15 fixed upon the loop-taker shaft 16 which is mounted in bearings 17 and 18 depending from the bed-plate 1.

Fixed upon the forward end of the shaft 16 by means of a set-screw 19 is a tubular hub 20 sustaining by means of the radial arms 21 the cup-shaped body 22 of the loop-seizing member of the loop-taker which is 120 formed with a central thread-cavity having in its inner wall the annular raceway 23 whose outer wall is afforded upon one side by the overhanging lip of the removable segmental section 24 of the loop-taker body. 125

The loop-taker body is formed with the usual peripherally disposed beak 25 having the point at its outer end backward of which

is the loop-distending shoulder 26. Extending toward but having its point spaced slightly from the beak 25 is the loop-discharging tail or spur 27 which is shown in the present instance formed upon one end of the section 24. The point of the spur 27 is directed oppositely to the beak and is disposed slightly nearer the axis of rotation than the outer face of the beak.

10 The thread-case is shown formed in separable sections, including a body section or carrier 28 and a cap section or thread-holder 29. The body section is shown provided intermediate its ends with the usual peripheral 15 annular bearing rib 30 formed at one end with a loop-detaining shoulder 31 co-operating with the inclined inner loop-distending edge of the beak 25 in the initial distention of the needle-thread loop, this bearing rib 20 entering the raceway 23 of the hook. On the side of the thread-case section 28 opposite that occupied by the shoulder 31 is the segmental guard-rib 32 which is disposed at or closely adjacent to the inner end of the 25 section 28 and terminates abruptly in a loop-restraining shoulder 33 at the end adjacent the shoulder 31 (Fig. 7) for engagement with the thread-loop upon and subsequent to its arrival at cast-off position.

30 The loop-taker body is cut away at 34 to afford clearance for this guard-rib. The thread-case section 28 is provided upon its cast-off side with a forwardly extending loop-absorbing flange 35 having an upwardly and outwardly inclined outer edge 36. At the extremity of the flange 35 adjacent the loop-seizing position the thread-case body is formed in its front face with a notch 37 of which one side wall is afforded 35 by the end of the flange 35 and the lower opposite side wall affords a shoulder which is undercut at 38 to receive the lower thread led from the thread-case to the work. The notch 37 loosely embraces the flat extremity 40 of the rearwardly extending holding finger 39 of the stationary holding arm 40 secured by a screw 41 upon the under face of the bed-plate 1.

At a point substantially diametrically opposite the notch 37 the thread-case 28 is provided with a projection 42 which affords a shoulder or abutment 43 adapted for engagement by a laterally extending vibratory finger 44 upon an extremity of the rock-shaft 45 which is journaled in a bearing sleeve 46 secured within an aperture of the bearing 18. Through the operative movements of the shaft 45 the finger 44 periodically shifts the thread-case circularly to open 50 a loop-release passage between the stationary holding finger 39 and the undercut wall of the notch 37.

The thread-case section 28 is provided upon its inner end with a cross member 47

from which rises the axial pin 48 upon 65 which is journaled the tubular post of well-known form disposed centrally of the cap section 29 and upon which is mounted the bobbin 49 carrying the mass of lower thread 50.

70 One of the radial arms of the loop-taking member is formed with a radial lubricant duct 51 which extends outwardly from the bore of the hub and merges into a substantially radial lubricant cavity 52 which is closed laterally at the inner face of the arm 21 by an angular shell or hood 53 which is open at its inner end rearwardly of said arm (Figs. 4 and 5). This lubricant cavity is designed to be filled with wicking or other 75 absorbent material to retain a supply of oil introduced either from the inner end of the cavity or through the hub 20. The outer end of the cavity 52 is connected by one or more passages 54 with the raceway 23 80 through which lubricant may be supplied to maintain the bearing between the thread-case and the loop-taking member properly lubricated.

85 The shaft 16 is shown provided with an axial lubricant passage 55 having at one end a transverse branch 56 in register with the duct 51 of the loop-taker, and at the other end a second transverse branch 57 leading outwardly to its periphery which is preferably formed with a shallow groove 58 extending around it for constant communication with a lubricant passage 59 extending downwardly from the top of the bed-plate through the bearing 18 and the bushing 18' 100 surrounding the shaft 16. By the means described, the bearing of the thread-case within the loop-taking member may be maintained properly lubricated by introduction of oil from above the bed-plate through the 105 passage 59, or by application of oil to the contained absorbent packing through the mouth of the lubricant cavity 52.

110 Connected to and rotating with the main-shaft 9 is the take-up disk 60 having upon its face the elongated lug 61 to which is secured by suitable means the guard-ring 62. Adjacent the lug 61 is a curved slot 63 in which works the stud-pin 64 which moves from one to the other end of the slot in the 115 rotation of the take-up disk 60.

120 The stud-pin 64 is carried by the free end of the vibratory lever 65 which is fulcrumed at its opposite end upon the pin 66 sustained by the disk 60. Intermediate its ends, the lever 65 has an arrangement 67 formed with a rectangular opening which embraces a slide-block 68 apertured to fit the stationary eccentric 69 fixed upon the cross-member 70 of the bracket-arm head 4. The crank-pin 125 8' carries a boss 71 arranged concentrically with the needle-actuating shaft 9 and journaled in a bearing aperture of the stationary

eccentric 69. The disk 60 is secured by means of the fastening screws 72 to the outer end of the boss 71.

Through the described connections, the disk 60 and guard-ring 62, spaced therefrom, rotate in unison with the needle-actuating shaft, the lever 65 performing its operative accelerated movement to move the stud-pin 64 from one to the other end of the slot 63 in the thread-drawing semi-rotation of the take-up, and performing its return movement in the succeeding semi-rotation. The needle-thread α is in practice led from the source of supply through the tension device 73 and thence through the suitably apertured thread-guide 74 at the side of the take-up disk, from which it is led intermediate the disk 60 and guard-ring 62 over the lug 61 and pin 64, thence downwardly through the guide-eye in the lower end of the needle-bar and through the needle-eye. The feed-dog 75 is mounted upon the feed-bar 76 which derives its endwise or work-advancing movements from a flexible connection with an arm 77 upon the feed-rock-shaft 78, and its rising and falling movements from the feed-lift rock-shaft 79 through a link connection 81 with a lateral crank-arm 80 of the rock-shaft 79. The rock-shafts 78 and 79 are provided with the usual lateral crank-arms 82 and 83, respectively, which are connected by means of the pitmen 84 and 85 with the usual actuating eccentrics 86 and 87 upon the main-shaft 9 in a manner well-known.

The feed-lift rock-shaft is provided rearward of the bearing 18 with a lateral crank-arm 88 to which is operatively connected through the link 89 the crank-arm 90 having its split hub clamped upon the rock-shaft 45 by means of the screw 91. As the feed-dog rises simultaneously with the ascent of the needle in the initial portion of the loop-casting operation, the described connection with the feed-lift rock-shaft causes the advance of the finger 41 to engage the thread-case shoulder 43, thereby imparting to the thread-case a slight turning movement which is completed in time to afford the requisite opening between the stationary holding finger 39 and the adjacent wall of the thread-case notch 37 for the escape of the needle-thread loop in the final action of the take-up thereon.

In the operation of the stitch-forming mechanism, in the rise of the needle after a descent to extreme lower position the needle-thread is seized by the point of the loop-taker beak 25, and while one limb of the loop thus formed is detained by the thread-case shoulder 31, the other limb is distended to the inner end of the thread-case during which time the take-up is giving up slack in its movement from substantially the

position represented in Fig. 12 to that of 65 Fig. 10. As the loop-taking member completes slightly more than a semi-rotation (Figs. 5 and 10) the loop-drawing action of the take-up begins, the inner limb of the loop slipping over the thread-case into engagement with the detaining shoulder 33 of the rib 32 (Fig. 5) while the free end of the loop begins its escape off the now upwardly inclined beak 25. At this time the needle-thread is forcibly engaged by the take-up 75 lug 61 and stud-pin 64 (Fig. 10) the accelerated movement of the latter thread-engaging element proceeding at the same time.

As the rotation of the hook proceeds while the take-up is moving from the position 80 shown in Fig. 10 to that represented in Fig. 11, the thread-loop is drawn off the point of the beak and upon the loop-discharging spur 27, resting in this movement upon the outer face of the beak and the guard-rib 32 (Fig. 85 9) which insure the support of the end of the loop beyond the outer face of the spur 27. As the loop-casting operation proceeds, 90 the loop, which is being progressively reduced in size under the action of the take-up, is maintained distended around the spur 27 and the loop-absorbing flange 35 (Fig. 6) so as to insure against kinking or twisting by premature release.

The thread-loop is thus held until the 95 point of the loop-discharging spur arrives at about loop-seizing position, when the loop is drawn up into the work and the stitch is set by the final action of the take-up (Fig. 11). The final action of the take-up is such that 100 the needle-thread remains taut only until the point of the needle is about to enter the work, when slack is given up rapidly to enable the loop-taker to readily distend the succeeding loop seized from the needle. 105

While the guard-rib 32 is herein represented as of less height than the bearing rib 30, it is so related to the latter that in the traverse of the needle-thread loop from the beak to the loop-discharging spur it is effectively shielded from rubbing upon the bearing rib and becoming soiled thereby. By providing the loop-detaining shoulder 33, the upper portion of the loop is prevented from slipping prematurely around the periphery of the thread-case as the loop-taker beak performs its upward movement from cast-off position, as represented in Fig. 5, thereby preventing the formation of undue slack in the loop kinking or tangling, usually 115 resulting in the formation of loops or knots upon the bottom of the finished work.

By reason of the abnormally large size of the loop-taking member and the thread-case to accommodate the desired increased thread 120 capacity, the size of the bearing between these parts of the loop-taker is correspondingly increased, and the special oiling facil-

ties herein shown and described are of importance to insure smoothness of operation; while the increased size of the needle-thread loop renders the effective control of the same of the utmost importance in order to secure uniform and perfect work.

By reference to Figs. 8 and 9, and particularly the former, it will be observed that the lower thread *b* is led from the delivery guide-eye 29' of the thread-case at the side opposite the loop-absorbing flange 35 and across the outer face of the cap section through the notch 37 in a substantially straight line. It is thus prevented from accidental escape by confinement in the channel formed between the flat inner end of the holding finger 39 and the bottom of the notch 37. The thread thus crosses beneath the finger diagonally so as to be engaged thereby at points extending substantially across the notch 37, which is made unusually wide for the purpose.

Having thus set forth the nature of the invention, what I claim herein is:—

1. In a sewing machine, in combination, a reciprocating needle, a loop-taking member performing two rotations for each reciprocation of said needle and formed with an axial thread-cavity and with peripherally arranged and oppositely directed loop-seizing beak and loop-discharging spur, a thread-case journaled in said loop-taking member and provided with means for restraining it against rotation with the same, and a take-up comprising a carrier performing a single rotation for each reciprocation of the needle, a plurality of thread-engaging elements rotating with said carrier, and means for imparting to one of said thread-engaging elements accelerated circumferential movements in the direction of rotation of said carrier in its action upon the needle-thread succeeding the arrival of a needle-thread loop at cast-off position around the thread-case.

2. In a sewing machine, in combination, a reciprocating needle, a loop-taking member performing two rotations for each reciprocation of said needle and formed with an axial thread-cavity and with peripherally arranged and oppositely directed loop-seizing beak and loop-discharging spur, a thread-case journaled in said loop-taking member and provided with a forwardly projecting loop-discharging flange at substantially loop-discharging position upon its cast-off side and with means for restraining it against rotation with the same, and a take-up comprising a carrier performing a single rotation for each reciprocation of the needle, a plurality of thread-engaging elements rotating with said carrier, and means for imparting to one of said thread-engaging elements accelerated circumferential movements in the direction of rotation of

said carrier in its action upon the needle-thread succeeding the arrival of a needle-thread loop at cast-off position around the thread-case.

3. A sewing machine loop-taker comprising a cup-shaped loop-seizing member provided with a thread-cavity having an annular raceway, and a thread-case having a peripheral bearing rib journaled in said raceway by which the thread-case is exclusively supported and interrupted on one side to 70 form a loop-detaining shoulder and an additional peripheral guard-rib at the end of the thread-case adjacent the bottom of said thread-cavity free from contact with the loop-seizing member and disposed within 80 a semi-circumference opposite that occupied by said loop-detaining shoulder.

4. A sewing machine loop-taker comprising a cup-shaped loop-seizing member provided with a thread-cavity having an annular raceway, and a thread-case having a peripheral bearing rib journaled in said raceway by which the thread-case is exclusively supported and interrupted on one side to 85 form a loop-detaining shoulder and an additional peripheral guard-rib at the end of the thread-case adjacent the bottom of said thread-cavity free from contact with the loop-seizing member and disposed within 90 a semi-circumference opposite that occupied by said loop-detaining shoulder and formed with a loop-detaining shoulder upon the end adjacent said shoulder of the bearing rib.

5. In a sewing machine, in combination, a reciprocating needle, a loop-taking member performing a plurality of rotations for each reciprocation of said needle and formed with an axial thread-cavity and with a peripherally arranged loop-seizing beak, a thread-case journaled in said loop-taking member and provided with means for restraining it against rotation with the same, and a take-up comprising a carrier performing a single rotation for each reciprocation of the needle, a plurality of thread-engaging elements rotating with said carrier, and means for imparting to one of said thread-engaging elements accelerated circumferential movements in the direction of 105 rotation of said carrier in its action upon the needle-thread succeeding the arrival of a needle-thread loop at cast-off position around the thread-case.

6. A sewing machine loop-taker having 120 a loop-seizing beak, a loop-discharging spur disposed oppositely to said beak and having its point depressed below the latter, a thread-case having a single bearing rib journaled within said loop-taker, and a 125 guard-rib at one side of said beak and spur, whereby a thread-loop is deflected from said bearing rib and upon said spur.

7. A sewing machine loop-taker having a loop-seizing beak, a thread-case having a single bearing rib journaled within said loop-taker, means for lubricating said rib, 5 and a guard-rib adjacent said bearing rib for deflecting thread from contact with said bearing rib, thereby preventing soiling of the thread.

In testimony whereof I have signed my name to this specification in the presence of 10 two subscribing witnesses.
